UNITED STATES PATENT OFFICE.

GEORG CANTIENY, OF BERLIN, GERMANY, ASSIGNOR TO KOHLENSCHEIDUNGS-GESELLSCHAFT M. B. H., OF BERLIN, GERMANY, A CORPORATION OF GERMANY.

BOILER STRUCTURE WITH PULVERIZED-COAL-BURNING FURNACE.

Application filed October 21, 1925, Serial No 63,867, and in Germany October 25, 1924.

This invention relates to water tube boilers whereby the furnace is covered over by the boiler elements like a roof and the coal dust is fed in an upward direction as shown 5 for instance in the Bettington boiler.

In boilers of this kind, hitherto, the air of combustion has been supplied together with the pulverized coal by the burners into an allside closed furnace and the flame was compelled to take an U-shaped path in the furnace before reaching the boiler heating surface. In such an arrangement difficulties must be expected as the size of the furnace has to be small compared with the boiler extension and therefore the flame does not burn 15 softly as required according to the latest new experience.

In order to avoid these difficulties it was proposed instead of pressing the flame into 20 a narrow furnace to develop same in the space between the roof-like boiler elements. This arrangement did not result satisfactorily as the upper boiler drums were exposed to the flame for direct contact and therefore 25 the seams of the boiler drums were likely to be damaged. The furnace arrangement of this kind is shown in German Patent No. 346,511.

According to the present invention all these 30 difficulties are avoided by a refractory arch installed below the upper boiler drums by which the flame is divided into two streams each of which floats through one half of the boiler and surrounds the entering mixture of 35 coal and air thus fostering the ignition of same.

Another object of the invention is to provide this refractory arch with air channels which have a plurality of openings to the 40 furnace. For this purpose the arch may be composed of two boxes advantageously supported by the front tube rows of the boiler elements.

Another object of the invention consists in 45 connecting the first row of boiler tubes coming from the lower drum with the upper drum of the opposite boiler element in such a manner that the tubes of the first rows cross each other and form a skeleton which may 50 support the boxes of the refractory arch.

Another object of the invention is introducing the coal and air in the form of flat streams having the broad extensions opposite each other and feeding supplementary 55 air through the openings of the arch in such

a manner, that the air streams flow between the flame streams thus enclosing the whole flame with fresh air and fostering combustion.

Another object of the invention is the installation of a water cooled screen in the lower part of the furnace connecting the lower boiler drums with headers which are arranged in suitable distance from each other between the lower boiler drums and 60 enclosing the upward directed burners between them. These headers are either connected with the upper boiler drums thus inserting the water screen in the water-circulation of the boiler or they may be adapted 65 as to serve as feed tubes for the water to be vaporized.

With the above and other objects in view, the invention consists in the improved water tube boiler and in the form, construction and 70 relative arrangement of its several parts as will be hereinafter more fully described, illustrated in the accompanying drawing, and subsequently incorporated in the subjoined 75 claims.

In the drawing wherein I have illustrated 80 one simple and practical embodiment of my present improvements

Fig. 1 represents a vertical section through the boiler structure and Fig. 2 is a fragmentary section taken on the line 2—2 of Fig. 1.

Referring in detail to the drawing *a* designates the furnace which is placed between the two lower boiler drums *b* and the lower extension of which is formed as ashpits *c*. 90 The burners *d* are arranged in a longitudinal row in parallel relation to the boiler drums between the hopper-like ashpits. The burners are adapted to blow the pulverized coal and air mixture in an upward direction. In 95 the upper part the furnace is limited by the refractory walls *e* which are supplemented to boxes *h* by walls *f* and *g*. These boxes are connected with the furnace by a plurality of openings *i*. The refractory walls *e* are provided throughout their length with spaced upcomer tubes *k* which connect the lower boiler drums with the upper drums of the 100 opposite boiler elements respectively.

The other upcomer tubes *m* and the downcomer tubes *n* connect the boiler drums with each other in the usual manner and are so arranged that there is sufficient space between them and the front tube rows *k* for the arrangement of the refractory boxes *h*. 110

The combustion may be observed through openings *o* in the opposite transverse walls of the furnace.

In the lower part of the furnace and opposite to the ashpits suitably spaced tubes *p* of water screens are arranged which create a cooling zone between the special furnace and the ashpits in which passing therethrough the incombustible melted ash particles are cooled and granulated. The water screen tubes connect the lower boiler drums *b* with longitudinally arranged headers *q* and have a slight ascent in the water-flow direction. These headers *q* enclose between them the burners thus cooling same and avoiding by their granulating effect the covering of the burners by a layer of slag. The headers may be connected by down-comers with the upper drums of the boiler elements whereby the cooling tubes above the ashpits are inserted into the water circulation of the boiler; they may also be connected with the water feeding device thus serving as feed tubes for the water to be evaporated.

According to the invention the burner nozzles have a flat cross section so as to form flame streams of little thickness whereby the small extensions of the flame surfaces are lying opposite to the evaporating surfaces of the boiler elements. Furthermore the openings in the refractory arch are arranged in such a manner that the air streams are introduced between the flame streams thus delivering additional oxygen to the whole surface of the flame streams (see Fig. 2).

The number of the air delivering openings in the arch and the downward extension of this arch may be varied according to the requirements of each installation. At all events it is possible in a very simple manner to supply the flame with sufficient supplementary air so that complete combustion may be obtained.

As it is shown in the drawing the pulverized coal and air mixture is introduced into the furnace in an upward direction by the burners. The upward flow is stopped partly by the suction in the boiler flues and partly by the refractory arch below the upper boiler drums. Hence, the flames take a downward path surrounding the entering stream fostering the ignition of same which however substantially is effected by the radiant heat of the refractory arch. Then the gases enter the boiler in two separated streams in divergent directions. It will be seen that on the point where the flames take a downward directed path supplementary air is admitted gradually so that a very soft and complete combustion is obtained.

The boiler structure as shown in the drawing is especially adapted to be arranged in such cases where the boiler extension must be limited as much as possible and where it is not allowed to arrange large furnaces out-

side the boiler. Such requirements may for instance ever exist in vessels where it is necessary to have boilers of small extensions but of great efficacy.

While I have herein shown and described one practical embodiment of my present improvements, it will nevertheless be understood that the essential features thereof might be incorporated in various other alternative structures, and I accordingly reserve the privilege of adopting all such changes in the form, construction and relative arrangement of the several parts as may be fairly embodied within the spirit and scope of the invention as claimed. 80

I claim:

1. The combination with a water tube boiler formed by two separate boiler elements of a pulverized coal burning furnace arranged between said boiler elements, extending 85 downwardly into two ash hoppers, upwardly directed fuel burners arranged between said ash hoppers, water cooled screens above said ash pits connected into the circulation of the boiler including headers adjacent the 90 burners.

2. The combination with a water tube boiler formed by two separate boiler elements, of a pulverized coal burning furnace arranged between said boiler elements, means in the 95 lower part of said combustion chamber for admitting fuel to be burned in an upward direction, cross connections between said boiler elements, a refractory arch supported by said connections, and outlets in the lower part of 100 said combustion chamber through which the products of combustion pass to the boiler elements.

3. The combination with a water tube boiler formed by two separate boiler elements, 105 of a pulverized coal burning furnace arranged between said boiler elements, means in the lower part of said combustion chamber for admitting fuel to be burned in an upward direction, cross connections between said boiler 110 elements, and a refractory arch supported by said connections and extending downwardly from the point of intersection of said cross connections, together with outlets below said arch for the products of combustion to pass 115 from the combustion chamber over the boiler elements.

4. The combination with a water tube boiler formed by two separate boiler elements, of a pulverized coal burning furnace arranged 120 between said boiler elements, means in the lower part of said combustion chamber for admitting fuel to be burned in an upward direction, cross connections between said boiler elements, air boxes supported by said connections, and means for admitting air from said boxes to the combustion chamber of the furnace. 125

5. The combination with a water tube boiler formed by two separate boiler elements, of 130

5 a pulverized coal burning furnace arranged between said boiler elements, means in the lower part of said combustion chamber for admitting fuel to be burned in an upward direction, cross connections between said boiler elements, and refractory air boxes supported by said connections and arranged to constitute a refractory arch for the furnace.

6. The combination with a water tube boiler formed by two separate boiler elements, of a pulverized coal burning furnace arranged between said boiler elements, upwardly directed fuel delivering nozzles arranged in a row at the bottom of said furnace, a hollow refractory arch defining the top of said furnace, air inlets for delivering air from the hollow portion of the arch to the interior of said furnace, and cross connections for the boiler elements comprising two rows of spaced tubes, said air inlets being located in the space between said spaced tubes.

10 15 20 25 7. The combination with a water tube boiler formed by two separate boiler elements upwardly converged towards each other, said boiler elements including upper and lower drums and interconnecting tubes, of a pulverized coal burning furnace arranged between said boiler elements extending downwardly into two ash hoppers, upwardly directed fuel delivering nozzles arranged between said ash hoppers and in a row in parallel relation to the boiler drums, and a refractory arch in the upper part of the furnace arranged below the upper boiler drums.

30 35 40 45 50 ized coal burning furnace arranged between said boiler elements extending downwardly into two ash hoppers, upwardly directed fuel delivering nozzles arranged between said ash hoppers and in a row in parallel relation to the boiler drums, and a refractory arch in the upper part of the furnace arranged below the upper boiler drums.

8. The combination with a water tube boiler formed by two separate boiler elements upwardly converged towards each other, said boiler elements including upper and lower drums and interconnecting tubes, of a pulverized coal burning furnace arranged between said boiler elements extending downwardly into two ash hoppers, upwardly directed fuel delivering nozzles arranged between said ash hoppers and in a row in parallel relation to the boiler drums, and a refractory arch in the upper part of the furnace arranged below the upper boiler drums, said arch being provided with openings and means for delivering supplementary air therethrough into the furnace.

In testimony whereof I affix my signature.
GEORG CANTIENY.
